Application January 11, 1951, Serial No. 205,557

6 Claims. (Cl. 120—32)

1

This invention relates to supporting structures for holding manuscript or typewritten sheets and for moving such sheets, a line at a time, into a reading position.

The invention is designed for use by typists who transcribe written or printed characters by means of a typewriter. For such an application the copy holder should be small, light, and capable of being quickly placed at a convenient position near the typewriter by the operator.

The present invention employs a scroll compartment for storing unused portions of the paper. A rotatable shaft carrying two cylindrical rubber rollers in resilient contact with a flat plate is employed to draw the paper sheet from the scroll compartment. The shaft is turned by predetermined increments so that after each shaft rotation a new line of character is visible above a horizontal guide. In order to equalize the pressure on the two rubber rollers and to compensate for inequalities in the paper thickness the flat plate is pressed against the rollers by means of a spring having a single contact point, thereby allowing the plate to rotate about a central vertical axis.

One prior art copy holder, designed along somewhat similar lines, employs a double roller, pivoted at the central portion of the shaft to afford the same means of compensation. Such a mode of compensation has inherent structural disadvantages because the rollers must be power driven at the same time they conform to the movements which provide the equalizing action.

One of the objects of this invention is to provide an improved copy holder which avoids one or more of the disadvantages and limitations of prior art arrangements.

Another object of the invention is to reduce the cost of manufacture of copy holders by providing a simple design, the parts of which may be easily assembled.

Another object of the invention is to provide a copy holder of triangular cross section suitable for supporting a stenographic note book.

Another object of the invention is to provide an adjustable interponent for varying the incremental movement of the paper.

The invention comprises a copy holder for moving paper into a reading position, and includes a paper storage compartment, a rotatable paper feed member for frictional engagement with one side of the paper, and a flat plate for sliding engagement with the other side of the paper. The flat plate is resiliently mounted so as to press against the rubber rollers in a pressure equalizing

2

manner but is restrained from sidewise and vertical motion. A manually operated lever mechanism actuates the paper feed member to move the paper a predetermined distance so that another line of characters is visible above a guide member.

For a better understanding of the present invention, together with other and further objects thereof, reference is made to the following description taken in connection with the accompanying drawings.

Fig. 1 is a side view of the copy holder, showing the position of the paper, indicated by a dotted line.

Fig. 2 is a sectional view taken along line 2—2 of Fig. 1.

Fig. 3 is a sectional view showing the flat plate, part of the resilient member, and the upper end of the scroll storage compartment.

Fig. 4 is a front view of the copy holder.

Fig. 5 is a sectional view of the paper feeding means showing the ratchet mechanism and the normal position of the flat pressure plate.

Fig. 6 is a sectional view of the lower portion of the copy holder showing the actuating levers in their operated position.

Fig. 7 is a partial bottom view of the copy holder showing the stepped interponent used for adjusting the degree of the paper movement.

Referring now to the figures, a base plate 10, formed with two bent-over portions, supports a back plate 11 and a front plate 12. These plates are riveted or spot welded to the base 10 by means of bent portions 13 and 14. Near the top edge of back plate 11, a bracket 15 is secured which rotatably supports a shaft 16. The shaft 16 has secured thereon two rubber rollers 17 and 18, and a ratchet wheel 20. The ratchet wheel is positioned about midway between two end bearings 40 and 41 and is engaged by a stationary pawl 21 and a movable pawl 22. The stationary pawl 21 is secured to the back plate 11 by a shoulder rivet 23 which also acts as one of the guides for the movable pawl 22. The movable pawl is formed with a slot 24, the upper edge of which engages the teeth on ratchet wheel 20 and turns the paper feeding member when the movable pawl is pulled down. The movable pawl 22 extends along the inside surface of the back plate 11 to a point near the base plate 10 where it is coupled to a lever 25. The movable pawl is resiliently urged toward its upper position by a spring 26 which is attached at one of its ends to a bent-out tab 27, and at the other end to the lower extremity of 55 the stationary pawl 21.

Lever 25 extends through a slot 28 in the base plate to make a pivoted connection with a second actuating lever 30 and then extends back through the same slot to rest on a fulcrum point near the front of the holder. A projection 25A extends through a second slot and holds the lever in place. The second lever 30 is fulcrumed by a projection 30A in a hole 31 in the base plate near the rear of the holder and extends through a slot in the base plate 10, then through a slot 32 in the front plate 12, and is terminated by a handle 33 in front of the copy holder and in easy reach of the operator. The two levers 25, 30 are held in pivoted engagement by a short shaft 34. Fig. 6 shows the position of the levers when the handle 33 is depressed to its lowest position. Fig. 1 shows the position of the levers after they have been returned to normal by the action of spring 26.

A scroll storage compartment 40 occupies most of the space between the front and back plates 12 and 11. It is secured by rivets 41 or other suitable fastening means to the inside face of front plate 12 and is formed with a smooth spiral section so as to receive a paper sheet 42 (indicated in dotted lines) and roll it into the compartment with a minimum of friction. The scroll compartment contains a slot 43 at its upper end so that a pressure plate 44 may be pivotally mounted by means of an extension 44A which is loosely secured by a shoulder rivet 45.

The pressure plate 44 is resiliently pressed against the two rubber rollers 17, 18 by means of a flat spring 46 which is secured by two rivets at its lower end and is formed with a slot 47 at its upper end. The slot engages a shoulder rivet 48 in slidable engagement so that the plate 44 is resiliently pressed against the rollers 17, 18, but is restrained from lateral movement. The single pivot at rivet 45 is loose enough to permit the plate 44 to have a freedom of motion toward and away from the rollers and also a motion about a vertical axis through the center of the plate. At the same time the construction prohibits a vertical motion so that the top edge always engages the rubber rollers at the tangential line.

In order to provide a straight edge which will cover the entire width of a standard sized letter sheet, a removable guide 50 is mounted on the outside face of plate 44 by means of two shoulder rivets 51 which fit into two slots in the guide. A curved up portion 52 is provided to act as a convenient handle to pull the plate 44 away from the rollers when a sheet of paper is to be inserted. When paper sheets are used which are considerably wider than the standard size, a wider guide can be substituted for the standard.

The paper feeding means is generally arranged to move the paper in increments which are equal to a double or triple line spacing on a standard typewriter. When it is desired to move the paper in smaller increments, an interponent 55, mounted on the bottom of the base plate 10, is rotated on a pivot 56 so that a stepped portion 57 moves above the lever 30 and limits its motion. The steps are formed on a turned over portion of an arcuate projection and are generally made in closely graduated heights so that the operator has considerable latitude in making incremental adjustments. A turned over portion 58 is provided to facilitate manual setting.

To operate the copy holder, the typist first pulls handle 52 toward the front of the machine, separating the plate 44 from the rubber rollers 17, 18. Then the typewritten sheet or manuscript is in-

serted between the rollers and the plate and pushed into the scroll storage compartment. Handle 52 is released after the paper sheet has been positioned to show a line of characters just above the upper edge of guide 50. The first line is then copied after which the second line is brought into view by manually depressing handle 33. It will be evident from Figs. 1 and 5 that all the lines on the inserted sheet can be made to show above the edge of the guide 50, including the last line on the paper.

While there have been described and illustrated specific embodiments of the invention, it will be obvious that various changes and modifications may be made therein without departing from the field of the invention which should be limited only by the scope of the appended claims.

I claim:

1. A copy holder for moving a paper sheet into a reading position comprising, a base plate, front and back plates secured to the base plate, a paper feed mechanism including a rotatable roller mounted on the back plate for frictional engagement with one side of the paper, a movable flat plate for sliding engagement with the other side of the paper, the movable plate formed with a projection which extends downwardly to a point near the base plate, the lower portion of the projection mounted on the front plate by a loose pivot connection, thereby giving the movable plate two degrees of motion, and a flat spring for resiliently stressing the top portion of the movable plate toward the roller, the spring having its lower end secured to the front plate and having its upper end slidably engaging the top portion of the movable plate.

2. A copy holder for moving a paper sheet into a reading position comprising, a base plate, front and back plates secured to the base plate, a paper feed mechanism including a rotatable roller mounted on the back plate for frictional engagement with one side of the paper, a movable flat plate for sliding engagement with the other side of the paper, the movable plate formed with a projection which extends downwardly to a point near the base plate, the lower portion of the projection mounted on the front plate by a loose pivot connection, thereby giving the movable plate two degrees of motion, a flat spring for resiliently stressing the top portion of the movable plate toward the roller, the spring having its lower end secured to the front plate and having its upper end slidably engaging the top portion of the movable plate, and a manually operable lever means for actuating the paper feed mechanism to move the paper a predetermined distance so that another line of characters is visible above a guide member.

3. A copy holder for moving a paper sheet into a reading position comprising, a base plate, front and back plates secured to the base plate, a scroll storage compartment for the paper sheet positioned between the front and back plates, a paper feed mechanism including a rotatable roller mounted on the back plate for frictional engagement with one side of the paper, a movable flat plate formed with a projection which extends downwardly to a point near the base plate, the lower portion of the projection mounted on the front plate by a loose pivotal connection, and a flat spring for resiliently stressing the top portion of the movable plate toward the roller, the spring having its lower end secured to the front plate and having its upper end slidably engaging the top portion of the movable plate thereby permitting

the movable plate to move about a vertical axis as well as a horizontal axis.

4. A copy holder for moving a paper sheet into a reading position comprising, a base plate, front and back plates secured to the base plate, a scroll storage compartment for the paper sheet positioned between the front and back plates, a paper feed mechanism including a rotatable roller mounted on the back plate for frictional engagement with one side of the paper, a movable flat plate formed with a projection which extends downwardly to a point near the base plate, the lower portion of the projection mounted on the front plate by a loose pivotal connection, and a flat spring for resiliently stressing the top portion of the movable plate toward the roller, the spring having its lower end secured to the front plate and having its upper end coupled to the top portion of the movable plate by a pin and slot connection thereby permitting the movable plate to turn about a vertical axis but restricting its motion parallel to the axis of the roller.

5. A copy holder for moving a paper sheet into a reading position comprising, a base plate, front and back plates secured to the base plate, a paper feeding mechanism including a roller mounted on the back plate for frictional engagement with one side of the paper, and a movable flat plate for sliding engagement with the other side of the paper, the movable plate pivotally mounted so as to permit motion around an axis which is parallel to the length of the front plate, said movable plate resiliently stressed toward the roller by a flat spring which slidably engages the movable plate at a point adjacent to its upper edge.

35

6. A copy holder for moving a paper sheet into a reading position comprising; a base plate; front and back plates secured to the base plate; a paper feed mechanism including a rotatable roller mounted on the back plate for frictional engagement with one side of the paper; a movable flat plate for sliding engagement with the other side of the paper, the movable plate pivotally mounted so as to permit motion around an axis which is parallel to the length of the front plate, said movable plate resiliently stressed toward the roller; and a flat spring, the lower end of which is secured to the front plate and the upper end of which slidably engages the movable plate at a point adjacent to its upper edge.
